[57] **CLAIM**

The ornamental design for an escalator motion detecting control device, as shown and described.

DESCRIPTION

FIG. 1 is a perspective view of the escalator motion detecting control device embodying the design of the present invention;

FIG. 2 is a front elevational view thereof;

FIG. 3 is a rear elevational view thereof;

FIG. 4 is a side elevational view thereof, the side opposite being a mirror image of the side shown in FIG. 4;

FIG. 5 is a top plan view thereof;

FIG. 6 is a bottom view thereof; and,

FIG. 7 is a perspective view showing the placement of the device with respect to an escalator, with the escalator being shown in broken lines as it is not part of the claimed invention.

FIG. 1.

FIG. 4.

FIG. 2.

FIG. 3.

FIG. 5:

FIG. 6
